UNITED STATES PATENT OFFICE.

ARTHUR F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

Application filed September 23, 1921. Serial No. 502,666.

To all whom it may concern:

Be it known that I, ARTHUR F. PYM, a subject of the King of England, residing at Lynn, in the county of Essex and Commonwealth of Massachusetts, have invented certain Improvements in Methods of Making Shoes, of which the following description, in connection with the accompanying drawings, is a specification, like reference characters on the drawings indicating like parts in the several figures.

This invention relates to methods of making shoes; particularly to methods of making turn shoes and to lasts for use in the practice of such methods.

In the manufacture of turn shoes it is usual to provide a first last having thereon a sole with its exposed face shouldered and channeled. An upper turned inside out is applied over the last and sole and then lasted and sewed to the between substance about the periphery of the sole except at the heel portion. The first last is now removed, the shoe turned right side out and placed upon a second last which may be the same as the first last but preferably is larger, for example, by a half size, so that the space inside the shoe previously occupied by the sole is taken up. The free end portion of the sole is now turned upwardly and a combined heel-seat pad and shank stiffener inserted beneath the sole and inside the upstanding margin of the upper and counter about the heel-seat but outside of the lining which is folded down upon the heel plate of the last. The heel-seat lasting operation, which ensues, consists in folding the upstanding margin of the upper and counter down upon the heel-seat pad and securing it there, the end of the sole being still bent upwardly away from the heel-seat to permit this operation. Since the heel-seat pad at this time is unsecured either to the last or to the sole, it may be moved forwardly or otherwise displaced, in which event it becomes difficult or impossible to last the shoe with a good angle or corner in the lasted upper where it is turned from the plane of the side of the last into the plane of the heel-seat.

An object of this invention is to provide

a last and method of making turn shoes by which displacement of the heel-seat pad prior to or during the heel-seat lasting operating is prevented and by which better heel-seat lasting will result.

In the practice of the invention, a shoe bottom part, for example a heel pad, is located in definite predetermined relation to the heel-seat of a last and is held from movement relatively to the last in the plane of the last bottom, in a manner which permits separation of the part and last in a direction perpendicular to the last bottom. Preferably the part and last are yieldingly locked against such separation. The locating and holding means for the pad and last may comprise co-operating projections and holes definitely spaced to hold the part and last in predetermined relation so that the edge 70 face of the pad will substantially coincide with the edge of the heel-seat.

As herein shown, two pins project above the surface of the last bottom and are resiliently depressible flush with the surface 75 of the last, their longitudinal axes being in outwardly divergent relation to each other to produce a locking effect. The heel pad is provided with two holes each of which is spaced from the rear end of the pad a distance equal to the distance of the corresponding pin from the end of the last. The pad is placed in proper position on the last bottom and pressed down, whereupon, because of the angular relation of the axes 80 of the pins to each other, the pad is held and relative movement of the last and pad in the plane of the last bottom is prevented. The last is now ready to be inserted as a second last into a shoe which has been lasted 85 upon a first last and turned in the usual manner. The end of the sole is raised and the upper, counter and lining lasted inwardly upon the heel pad which, being unable to shift in the plane of the last bottom 90 because of the pins, is held in exact proper relation to the heel-seat and insures the formation of an even and proper angle about the heel-seat between the side of the last and the overlaid margin of upper materials 100 and counter.

The pins present no obstacle to the re-

moval of the last since the different directions of the pins correspond respectively to the usual successive relative movements between the last and the shoe necessary to disengage the last from the shoe.

In the drawings,

Fig. 1 is a side view, partly in section, of my improved last in a turn shoe before turning, the upper having been sewed to the sole except about the heel-seat;

Fig. 2 is a view of the last with a heel pad and stiffener located thereon in accordance with this invention and ready to be inserted in a shoe after it is turned;

Fig. 3 is a side view of the shoe and last, partly in section, after the step of lasting the heel-seat has been performed;

Fig. 4 shows the last and shoe, partly in section, after the step of removing the last has been initiated; and

Fig. 5 is a partial plan view of Fig. 2.

The last is provided with two depressible pins 2, 4 which normally project a short distance above the bottom of the last. Each pin is mounted in a cylindrical casing 6 closed at its bottom except for a hole through which the pin 2 freely passes. The pin carries a collar 8 fixed thereto which slides freely in the casing. Between the collar 8 and the bottom of the casing 6 is a spring 10 which normally forces the pin outwardly of the casing until the headed lower end 12 of the pin engages the casing. The casing is driven into a suitable hole 14 in the last which hole is deep enough to allow the outer end of the pin to be depressed flush with the last bottom before the opposite end of the pin hits the bottom of the hole. The pin 4 is preferably mounted exactly similarly to the pin 2 except that the longitudinal axis of the hole 16 in which the pin 4 is mounted is inclined to the longitudinal axis of the hole 14 in which the pin 2 and its casing 6 are held. As shown, the pin 4 is inclined upwardly and forwardly relatively to the pin 2 and to the last. The pin 4 is also preferably offset laterally with respect to the longitudinal median plane of the last, as shown in Fig. 5, so that the pin 4 does not interfere with the metal stiffener 20 usually attached to or embedded in the heel pad 22. In order to locate accurately and secure firmly the pins in the last, it is preferable that the holes for the pin casing be made through the metal heel plate 24 which is attached to the heel-seat portion of the last. The heel plates may be provided, at the time of their manufacture, with two holes properly located and corresponding substantially in size to the diameter of the casing 6, and after attachment of the heel plate to the last the holes in the plate will serve to locate the holes which are bored in the last to receive the casings, that is, the heel plate serves as a jig for boring the

casing holes. In other respects the last may be similar to lasts usually employed in the manufacture of turn shoes.

In the practice of the method of the present invention an upper 25 inside out and a sole 26 are assembled upon a last, lasted and sewed together in the manner usually practiced in the manufacture of turn shoes, the seam extending from one side of the heel-seat about the periphery of the shank and forepart to the other side of the heel-seat, leaving the heel-seat portion unattached. Since the pins 2 and 4 are depressible they do not interfere with the attachment of the sole to the last when used as a first last. The shoe, after the turn sewing operation, is shown in Fig. 1.

The shoe is next removed from the last and turned. Then either the same last or a similar last one-half size larger has placed upon it a heel pad and stiffener 22, 20, which has previously been provided with suitable holes spaced and positioned in exact accordance with the positions of the pins at the plane of the heel-seat. The rear hole in the heel pad is placed over the pin 2 and the pad pressed down against the pin 4 which is thereby depressed flush with the plane of the heel-seat. By slight manipulation of the pad, if necessary, the pin 4 is caused to snap up through the forward hole in the pad, whereupon the pad, partly by reason of the divergent relation of the axes of the pins, is held upon the last, and, by reason of the accurate location of the pin holes, is positioned exactly as it should be with relation to the last and is securely held from longitudinal or lateral movement with respect to the last.

The last and pad are then inserted in the turned shoe, the free end of the sole turned back, and the heel-seat lasted down upon the pad 22 and secured, for example, by tacks 28 as shown in Fig. 3 which illustrates the shoe after the heel-seat lasting operation. During this operation the pad is prevented by the pins from shifting relatively to the heel plate of the last and a square and uniform angle between the upper and counter and their inturned flange portions is assured. The free end of the sole may now be nailed down to the pad and the inturned flanges of the upper and counter by the usual heel-seat nailing operation, the shoe being then in the condition shown in Fig. 4 and ready for the attachment of the heel which may or may not be attached before the last is removed. When the free end of the sole is nailed down to the heel seat it depresses the pins 2, 4, so that they project only through the thickness of the heel pad 22. This results in substantially unlocking the pad from the last, particularly when the ends of the pins are rounded as shown, to permit the last to be easily pulled. More-

over, in removing the last, either before or after the heel is attached, the pad 22 and last at the rear end are first separated in a direction perpendicular to the heel plate, that is, in the direction of the axis of the pin 2, which is thus released. As soon as this separation is enough to permit it, the shoe and last are also relatively moved longitudinally; since this compound movement is in the direction of the pin 4, it does not interfere with the last pulling operation.

Having thus described my invention, what I claim as new and desire to secure by Letters Patent of the United States is:

1. That improvement in the making of shoes which consists in providing a heel pad with openings in spaced relation longitudinally of the shoe, providing, on the heel-seat of a last, locating members arranged to engage the openings in the said pad and to locate the pad on the last in predetermined position in the proper lateral and longitudinal adjustment, placing said pad on the locating members on the last,

2. placing the last and pad in a turn shoe, and lasting the upper over the pad so located.

2. That improvement in making shoes which consists in providing a last with projections located at predetermined different distances from the heel end of the last with their axes in divergent relation, one of said projections being depressible, providing a shoe bottom part with holes corresponding in location to the location of the projections on the last, assembling the bottom part with one of the projections in register with one hole in said part, pressing the shoe bottom part against the depressible projection to cause the same to be depressed and to enter the second hole whereby the part is locked to the last bottom by reason of the divergent relation of the axes of the projections, then inserting a last in the shoe upper, and lasting the upper to the shoe bottom parts.

3. That improvement in the art of making shoes which consists in providing a last and a heel pad, one having in its heel-seat portion a plurality of recesses and the other having on its corresponding portion a plurality of projections to correspond with the recesses, said projections and recesses being equally spaced longitudinally of the shoe and each projection and its corresponding recess being spaced at the same predetermined distance from the heel end of the shoe, then assembling the bottom part on the last, the recesses and projections being in co-operative relation to hold the bottom part in predetermined position on the last

and to prevent relative longitudinal movement of the bottom part and last, then lasting the upper to the bottom part, and completing the shoe in the usual manner.

4. That improvement in making turn shoes which consists in providing a heel pad

and stiffener with openings in spaced relation longitudinally of the shoe, providing on the second last, pad locating members arranged to engage the holes in the pad and to locate the pad on the last in predetermined position in proper lateral adjustment and with its rear end flush with the end of the heel-seat, placing a pad on the locating member, inserting the last in the shoe, lasting the heel-seat, completing the shoe in the usual manner, and removing the last.

5. That improvement in making turn shoes which consists in providing locating members on the rear portion of the bottom of a last arranged with their axes in divergent relation, one at least of the members being depressible, providing a pad with a plurality of holes, placing the pad on the last with one of the holes over one of the members, forcing the pad against the other member to cause it to be depressed and its end brought into register with the other hole, allowing the member to rise in the second hole to lock the pad on the last in predetermined relation, inserting the last in the turned shoe, and completing the shoe in the usual manner.

6. That improvement in making turn shoes which consists in providing locating members on the rear portion of a last spaced apart longitudinally of the last and arranged with their axes in divergent relation, one at least of the members being depressible, providing a pad with holes spaced like the locating members, placing the pad on the last with one of the holes over one of the members, forcing the pad against the other member to cause it to be depressed and its end brought into register with the other hole, allowing the member to rise in the second hole to lock the pad on the last in predetermined relation, inserting the last in the turned shoe, completing the shoe in the usual manner, and removing the last first by an outward movement to disengage the rear member and then by a combined outward and longitudinal movement to free the other member from its hole.

7. That improvement in making turn shoes which consists in providing a last with a pin located substantially at the center of curvature of the heel end of the last and with a resiliently supported pin located forwardly of the first pin at one side of the longitudinal median line of the rear part of the last bottom and having its axis inclined to the last bottom, providing a combined heel pad and stiffener with holes spaced like the pins, the rear hole being at the same distance from the rear end of the pad as is the rear pin from the end of the last, assembling the pad upon the last with the rear hole in engagement with the rear pin, pressing down on the pad to cause the second pin to be depressed and brought in line

with the second hole and to project therein, inserting the last and pad in a turned shoe, lasting the rear portion of the upper to the pad, and removing the last from the 5 shoe first by an outward movement to free the rear pin and then by an outward and longitudinal movement to free the second pin.

8. That improvement in making turn 10 shoes which consists in providing a last with projections located at predetermined different distances from the heel end of the last with their axes in divergent relation, one at least of said projections being de- 15 pressible, providing a combined heel pad and stiffener with holes corresponding in location to the location of the projections on the last, assembling the pad with one of the holes in register with one hole in the pad, 20 pressing the pad against the depressible projection to cause the same to be depressed, causing the projection to enter the second hole whereby the pad is locked to the last bottom by reason of the divergent relation 25 of the axes of the projections, then inserting the last in a turned shoe and lasting the upper and counter to the heel-seat portion of the pad.

9. That improvement in the art of mak- 30 ing turn shoes which comprises providing a second last with projections located at predetermined different distances from the heel end of the last, providing a combined heel pad and stiffener with holes corresponding 35 in location to the location of the projections, assembling the pad upon the last with the holes in engagement with the projections, inserting the last and pad in a turned shoe and lasting the projecting margin of the 40 upper and counter to the heel portion of the pad, and completing the shoe in the usual manner.

10. That improvement in the art of making turn shoes which comprises providing a second last and a combined heel pad and 45 stiffener, one having a plurality of recesses and the other a plurality of projections to co-operate with the recesses, each recess and its co-operating projection being spaced at the same predetermined distances from the 50 heel end of the shoe, then assembling the heel pad on the last with the recesses and projections in co-operative relation to hold the pad in predetermined position on the last and to prevent relative longitudinal 55 movement of the pad and last, inserting the pad and last in a turned shoe, lasting the heel-seat of the shoe upon said pad, and then completing the shoe in the usual manner.

11. A last having on its heel-seat portion 60 two locating pins arranged with their axes in divergent relation, and spring means for maintaining one of the pins in extended position and permitting it to be depressed to enable a heel pad having two holes to be positioned on the last with one of the holes over one of the pins and then forced against the depressible pin to cause it to be depressed and its end brought in register with the other hole, the pin then rising in the 70 second hole to lock the pad to the last in predetermined position.

12. In a shoe last, a pin located substantially at the center of curvature of the heel end of the last, and a resiliently supported 75 pin located in the heel-seat forwardly of the first pin at one side of the longitudinal median line of the heel part of the last bottom and having its axis inclined to the last bottom.

In testimony whereof I have signed my name to this specification.

ARTHUR F. PYM.
